UNITED STATES PATENT OFFICE.

MATT KNEELAND, OF DIAMOND, MISSOURI, ASSIGNOR OF ONE-HALF TO SAMUEL B. VARNER AND WILEY G. WOODCOCK, OF GRANBY, MISSOURI.

PICK.

1,010,390.

Specification of Letters Patent. Patented Nov. 28, 1911.

Application filed May 18, 1911. Serial No. 627,925.

To all whom it may concern:

Be it known that I, MATT KNEELAND, a citizen of the United States, residing at Diamond, in the county of Newton and State 5 of Missouri, have invented certain new and useful Improvements in Picks, of which the following is a specification, reference being had therein to the accompanying drawing.

This invention relates to picks and has a 10 special reference to picks provided with removable points.

The invention has for its object to provide an improved pick having removable points so constructed and arranged in conjunction with the main body of the pick that not only will the points be securely and effectively fastened in place but also the joint connecting the points with the main body of the pick may be readily and effectively cleaned.

Referring to the accompanying drawings:—Figure 1 is a view of a pick and a portion of the handle, said pick being constructed in accordance with this invention.

Fig. 2 is an enlarged detail view of a portion of the pick in longitudinal section showing the joint connecting the detachable point with the main body of the pick. Fig. 3 is an enlarged detail view of a portion of 25 the pick in longitudinal section showing a modification of the joint for detachably connecting the point with the main body of the pick. Fig. 4 is an enlarged detail view 30 in perspective of a portion of the main body of the pick showing the socket with which the detachable joint is connected.

Fig. 5 is an enlarged detail view in perspective of one of the detachable points of 35 the pick constructed in accordance with this invention. Fig. 6 is a cross section on the line X—X, Fig. 2. Fig. 7 is an enlarged detail view in perspective of a portion of a pick showing a modification of the means 40 for connecting the point to the main body 45 of the pick.

In the accompanying drawings 1 indicates a pick and 2 the handle thereof broken away. The main body 3 of the pick is formed at each end with a dove-tailed slot 4 having 50 an open longitudinal portion located on the underside of the main body of the pick. The pick is provided with detachable points 5 each of which is formed with a dove-tailed projection 6 adapted to fit into the dove 55 tailed slot 4, the shouldered portion 7 of

the point abutting the end of the main body of the pick.

In order to detachably secure the point to the main body of the pick suitable means are provided, as for example, the reduced 60 projection 8 on the end of the dove tailed projection 6 which fits into a socket 9 at the inner end of the dove tailed slot 4, the shouldered end 10 of the dove tailed projection 6 abutting against the inner end of the dove tailed socket 4. The point is held in place by means of a screw 11 or other suitable 65 fastening device which is screwed through a hole 12 in the main body 3 of the pick, said hole being in alinement with a hole 13 in the projection 8, and with a hole 14 in the main body 3 of the pick, as shown in Fig. 2, the screw extending through the holes 12 and 13 and projecting into the hole 14. 75

It will be seen that by means of the foregoing construction the point 5 may be readily secured to the main body of the pick and may be firmly held in place therein.

In Fig. 7 is shown a modification of the 80 point in which a point 15 is formed with a dove tailed projection 16 having a reduced projection 17 at the end of the dove tailed projection 16, the projection 17 being provided with a suitable recess, as for example, 85 the transverse slot 18 which is adapted to be engaged by a screw 19 extending through a hole 12 in the main body of the pick.

In addition to the point being securely held in place on the main body of the pick 90 the dove tailed slot 14 owing to its shape permits of the dirt or other foreign matter which may accumulate therein being readily removed therefrom by means of a suitable instrument, as for example, the blade of a 95 knife.

By means of a pick constructed in accordance with this invention the points may be readily removed when broken and new ones 100 substituted therefor.

What I claim is:—

1. In a pick of the kind described, a main body having a dove tailed socket with a longitudinal slot in the underside of the body of the pick, and a socket at the inner 105 end of said dove tailed socket, and a hole in the main body of the pick extending transversely through said last named socket, a detachable pick having a dove tailed projection and a reduced projection at the end 110

of said dove tailed projection; said dove tailed projection being located in said dove tailed socket, and said reduced projection being located in the socket in the inner end 5 of the dove tailed socket, and means extending from the hole in the main body of the pick and through said socket in the inner end of the dovetail socket and engaging said reduced projection on the end of the dove- 10 tail projection of the point.

2. In a pick of the kind described, a main body portion formed with a dove tailed socket at each end thereof, with a longitudinal slot in the underside of the main body 15 of the pick, and a socket at the inner end of said dove tailed socket, and a hole in the main body of the pick opening into said

socket, detachable points, each of said points having a reduced dove tailed projection with a reduced projection having a recess, said dove tailed projection being located in said dove tailed socket and said reduced projection being located in the socket at the end of the dove tailed socket, and a screw extending through said hole in the main body 20 of the pick and engaging the reduced projection located in the socket at the inner end of the dovetail socket. 25

In testimony whereof I hereunto affix my signature in presence of two witnesses.

MATT KNEELAND.
